UNITED STATES PATENT OFFICE.

JOHN M. VERRE, OF CHESTER, PENNSYLVANIA.

ANTIBURSTING ATTACHMENT FOR TANKS, PIPES, &c.

1,355,721.

Specification of Letters Patent. Patented Oct. 12, 1920.

Application filed May 28, 1918. Serial No. 237,168.

To all whom it may concern:

Be it known that I, JOHN M. VERRE, a citizen of the United States, residing at Chester, in the county of Delaware and State of Pennsylvania, have invented certain new and useful Improvements in Antibursting Attachments for Tanks, Pipes, &c.; and I do hereby declare the following to be a full, clear, and exact description of the invention, such as will enable others skilled in the art to which it appertains to make and use the same.

My invention relates to improvements in anti-bursting attachments for tanks, pipes, etc.

An important object of this invention is to prevent tanks, pipes, etc., from bursting as a result of the expansion of water upon freezing.

A further object of the invention is to provide an anti-bursting attachment for tanks, pipes, etc., comprising a piston operating in an air cylinder, said piston being adapted to compress the air within the air cylinder, upon the increased pressure within the tank caused by the expansion of the water.

Other objects and advantages of the invention will be apparent during the course of the following description.

In the accompanying drawings forming a part of this specification and in which like numerals are employed to designate like parts throughout the same,

Figure 1 is a vertical longitudinal central sectional view through a tank having my improved anti-bursting attachment applied thereto,

Fig. 2 is a central longitudinal vertical section through an apparatus embodying my invention,

Fig. 3 is a section taken through a pipe, having my improved anti-bursting attachment applied thereto,

Fig. 4 is a vertical longitudinal section taken through a further modification of the invention,

Fig. 5 is a longitudinal sectional view through a vertical boiler, having my improved anti-bursting attachment applied thereto.

Fig. 6 is a side elevation of a section of pipe, having my improved anti-bursting attachment applied thereto, the same being shown in section,

Fig. 7 is a central vertical longitudinal

sectional view through a tank having my improved anti-bursting attachment arranged therein, the same being shown inverted, and,

Fig. 8 is a central longitudinal sectional view through a tank, having my improved anti-bursting attachment arranged therein.

In the drawings, wherein for the purpose of illustration is shown the preferred embodiment of my invention, the numeral 10 designates a tank having a top and bottom designated by the numeral 11, said tank having the usual inlet pipe 12 and an outlet pipe 13.

My invention comprises a cylinder 14 open at one end as at 15, said cylinder having arranged therein a piston 16. The piston 16 comprises a circular piece of cork 17 and a metallic disk 18. A cap 19 having screw threaded engagement with the open end of the cylinder 14 is provided with an annular flange 20 adapted to prevent the piston 16 from slipping out of the cylinder 14.

In the form shown in Fig. 1 spokes 21 serve to support the cylinder 14 centrally within a tank, though it is obvious that any suitable means may be employed to arrange the cylinder within the tank in the proper place.

Upon the expansion of the water within the tank as a result of freezing, an upward pressure will be exerted on the piston 16 within the cylinder with the result that the air within the cylinder will be compressed thus affording sufficient space to permit of the expansion of the water without bursting the tank.

In the modified form shown in Fig. 3, the cylinder 14 is in communication with a pipe 22, by a coupling 23. In this form it is obvious that the expansion of water caused by freezing causes the piston to partake of an upward movement in the same manner as the form shown in Fig. 1.

In the form shown in Fig. 4, the cylinder 14 is displaced by a substantially U-shaped cylinder, having one end open as at 24.

In the modification shown in Fig. 5, the cylinder 14 is in communication with a vertical pipe 25 having a T-coupling 26 connected with a nipple 27. An elbow 28 serves to connect the nipple 27 with the cylinder 14.

In the form of my invention shown in Fig. 6, a pipe 29 having elbows 30 at its ends serves to connect the cylinder 14 with a pipe 31. This particular form of the

invention prevents the escape of air from the cylinder 14, should the pipe 31 become inverted.

In the form shown in Fig. 7, the cylinder 5 14 is arranged within the tank 10 near the bottom thereof, and the cap 19 is dispensed with.

In the form shown in Fig. 8, the opening 10 in the cylinder 14 is arranged near the top of the tank 10 and the expansion of the water causes the air in the top of the tank to force the air within the cylinder within a smaller space.

In each form of the invention the piston 15 16, owing to the weight or the metallic disk 18 on the bottom of the cork member 17 and forming a part of the section, will be held downwardly within the cylinder 14 and the weight of the piston together with the frictional engagement of the cork 17 and disk 20 18 with the interior wall of the cylinder 14 will offer sufficient resistance to upward movement of the piston 16 within the cylinder 14 to prevent the piston from being moved upwardly by normal pressure of the water upon the under face of the disk 18. The piston 16, the main portion of which being formed of cork, will also cause an air and water tight fitting of the piston 16 25 within the cylinder 14, thereby preventing the air from escaping from the upper portion of the cylinder 14 about the piston 16 and at the same time preventing water from passing into the cylinder 14. Any water 30 which may reach the main portion of the cylinder 14 results in a swelling or an expansion of the cork portion 17 of the piston 16 and thereby causing a tighter fitting of the piston 16 within the cylinder 14 and increasing the friction and in this manner assisting in retaining the piston 16 in the lower end of the cylinder 14 until forced upwardly by the expansion of the water within the boiler, tank or pipe in which the cylinder 14 is positioned, owing to freezing of the water and upon such expansion of the freezing water the piston 16 will be forced upwardly within the cylinder 14. As soon 35 as the excessive pressure upon the bottom of the piston 16 is relieved by a rise in temperature and contraction of the water, however, the compressed air within the cylinder 14 will co-act with the piston 16 or metallic disk 18 thereof to return the piston 40 to its normal position within the lower end

of the cylinder 14. This is true of each form of the invention and it is believed that the operation may be clear without further detailed description thereof. 60

While I have shown and described the preferred embodiment of my invention, it is understood that I may make such minor changes in arrangement and construction of parts as will remain within the spirit of 65 the invention and the appended claims.

Having thus described my invention, what I claim is:

1. A device of the class described comprising the combination with a liquid reservoir, of a cylinder supported therein and having the lower end thereof open, a plug fitting within the cylinder at the open end thereof and adapted to be moved upwardly within the cylinder upon expansion of the liquid in the reservoir, said plug being adapted to move downwardly upon a decrease of the pressure against the under face thereof by gravity, and means to prevent said plug from moving out of the lower end of said cylinder. 70 75 80

2. A device of the class described comprising the combination with a liquid reservoir of a cylinder supported therein and having one end open, and a weighted plug adapted to be forced in one direction within said cylinder by expansion of water within the reservoir, said plug being adapted to move by its own weight and by expansion 85 90 of air working on an opposite face thereof upon contraction of the water in the reservoir.

3. In a device of the class described, the combination with a liquid reservoir, of a cylinder within said reservoir, and a weighted plug contacting with the walls of said cylinder and adapted to be operated by expansion of the liquid within the reservoir to force said weighted plug in one direction 95 100 within said cylinder and compress the air therein, said weighted plug being returned by its own weight and expansion of the air upon contraction of the water within the reservoir. 105

In testimony whereof I affix my signature in presence of two witnesses.

JOHN M. VERRE.
